UNITED STATES PATENT OFFICE.

CHARLES J. NASH, OF CHICAGO, ILLINOIS, ASSIGNOR TO UNIVERSAL DRAFT GEAR ATTACHMENT CO., OF CHICAGO, ILLINOIS, A CORPORATION OF ILLINOIS.

DRAFT-GEAR YOKE.

1,085,288.

Specification of Letters Patent. Patented Jan 27, 1914.

Application filed April 19, 1913. Serial No. 763,233.

To all whom it may concern:

Be it known that I, CHARLES J. NASH, a citizen of the United States, and resident of Chicago, county of Cook, and State of Illinois, have invented certain new and useful Improvements in Draft-Gear Yokes, of which the following is a specification, and which are illustrated in the accompanying drawings, forming a part thereof.

10 The object of the invention is to provide a cast steel yoke of great strength while of light weight.

The invention is especially adapted to yokes used in connection with so-called tandem spring gears, and it appertains to the forward end of the yoke and to the means for transmitting buffing stresses from the coupler to the follower plates.

The invention consists of a yoke of the Master Car Builders' type, having bearing abutments for the inner end of the coupler and the forward follower, such abutments being formed as integral parts of the longitudinal members of the yoke and being in box form, and being preferably united by integral pillars at the sides of the yoke.

In the accompanying drawings illustrating the invention, Figure 1 is a side elevation of the yoke; Fig. 2 is a detail perspective of the forward end of the yoke, some parts being broken away; Fig. 3 is a sectional detail on the line 3—3 of Fig. 2; and Fig. 4 is a sectional detail on the line 4—4 of Fig. 1.

35 The yoke comprises the usual longitudinal members 10, 11, united at their rearward ends, as shown at 12, and being provided at their forward ends with inturned lips 13, 14, for engaging forwardly directed shoulders on the shank of the coupler and having rivet holes 15, 16, to accommodate the rivets for securing the coupler to the yoke. The yoke is also provided with a bridge 17 substantially midway of its length, for engaging 45 the two intermediate followers of a tandem gear. This bridge may be of any preferred form of construction.

Near the forward end of the yoke, and so positioned as to form bearings for the inner end of the coupler shank, there is located a pair of abutments 18, 19, which are cast integral with the longitudinal members 10, 11, and on the inner faces thereof. These abutments are in box form, comprising the 55 transverse members to which the numerals

18, 19, are applied, and which are spaced apart, respectively, from the top and bottom longitudinal members of the yoke and are connected therewith by means of the end members 20, 21, and 22, 23, respectively. 60 These abutments are united by a pair of pillars 24, 25, located one at each end of the abutments and being preferably of less width than the abutments, the latter being of sufficient width to provide ample strength 65 for transmitting buffing stresses from the coupler to the forward follower against which their rearward faces are adapted to bear.

The pillars and the several walls of the 70 abutments are preferably of substantially the same thickness as the longitudinal members of the yoke, thereby facilitating the casting operation by avoiding the massing 75 of metal and the consequent liability of the production of weak castings. Preferably the walls of the abutments are coved or recessed midway between their side edges, as shown at 26, 27, for the purpose of reducing 80 the weight of metal and further facilitating the casting operation.

In the use of tandem gears the buffing 85 stresses tend to spread the longitudinal members of the yoke, and this tendency is overcome by the pillars 24, 25. In the manufacture of draft gears there is usually some variation in measurements, and it is frequently found that the thickness of the butt 90 of the coupler is somewhat less than the distance between the forward ends of the longitudinal members of the yoke, and it becomes necessary to draw these members down firmly upon the coupler. In order that this may be accomplished and a continuous bearing contact secured between the yoke members and the coupler, the pillars 24, 25, may be bent inwardly by the blow of a hammer without lessening their tensile strength. This flexure of the pillars is rendered possible by making them of comparatively little 95 width, as shown. The abutments 18, 19 relieve the securing rivets from strain incident to buffing stresses.

I claim as my invention—

1. In a yoke, in combination, a pair of 105 longitudinal members, abutments in box form formed on the inner faces of the longitudinal members, and positioned to receive the bearing of the butt of a coupler, and pillars uniting the abutments at their ends. 110

2. In a yoke, in combination, a pair of longitudinal members, abutments formed on the inner faces of the longitudinal members for receiving the bearing of a coupler butt and comprising members parallel with and spaced apart from the longitudinal members and end members uniting them with the longitudinal members.
3. In a yoke, in combination, a pair of longitudinal members, abutments formed on the inner faces of the longitudinal members

for receiving the bearing of a coupler butt and comprising members parallel with and spaced apart from the longitudinal members and end members uniting them with the longitudinal members, and pillars uniting the abutments and being in line with their end members. 15

CHARLES J. NASH.
